UNITED STATES PATENT OFFICE.

GEORGE A. PARMENTER AND STEPHEN H. PEIRCE, OF CAMBRIDGE,
MASSACHUSETTS.

TRACK-CLEANER FOR STREET-RAILWAYS.

SPECIFICATION forming part of Letters Patent No. 594,552, dated November 30, 1897.

Application filed October 9, 1897. Serial No. 654,659. (No model.)

To all whom it may concern:

Be it known that we, GEORGE A. PARMENTER and STEPHEN H. PEIRCE, of Cambridge, in the county of Middlesex and State of Massachusetts, have jointly invented certain new and useful Improvements in Track-Cleaners for Street-Railways, of which the following, taken in connection with the accompanying drawings, is a specification.

Our invention relates to track-cleaners for street-railway cars; and it consists in certain novel features of construction, arrangement, and combination of parts, which will be readily understood by reference to the description of the accompanying drawings, forming a part of this application, and to the claims hereto appended and in which our invention is clearly pointed out.

Figure 1 of the drawings is a sectional elevation of a portion of one end of a street-car with our invention applied thereto. Fig. 2 is a plan of the same with the floor of the car removed. Fig. 3 is a rear elevation of one of the track-scrapers and its carrier drawn to an enlarged scale. Fig. 4 is a side elevation of the same. Fig. 5 is a sectional elevation, the cutting plane being on line $x-x$ in Fig. 3. Figs. 6 and 7 are respectively an elevation and a transverse section of the guideway-stand and catch for the lifting-rod; and Figs. 8 and 9 are two elevations of a modified form of link connection, to be explained.

In the drawings, A is the truck-frame, B the car-wheels, C the sills of the car-body, D the dasher, and E the pilot-board, all of which may be of any well-known construction.

The pilot-board E has firmly secured to its inner vertical face above each track-rail a stand F, the upper end of which is provided with the two rearwardly-projecting ears or arms F', through the rear ends of which is inserted the bolt or rod a to form the rearward boundary of the slot or opening between said ears or arms, as shown in Fig. 5. The stand F also has pivoted thereto the slotted arm G, provided with the shoulder b to receive the end of the spring H, the tension of which tends to move the rear end of said slotted arm downward, and said arm G is also provided with the shoulder c to abut against said stand

F and thus limit the downward movement of the rear end of said arm G, as shown in Fig. 5.

I is a V-shaped scraper or plowshare, preferably of sheet-steel, firmly secured to the lower end of the vertical or nearly-vertical bar J, which extends through the slot in the arm G and between the ears F' of the stand F, as shown in Fig. 3.

The bar J has its upper end curved toward the end of the car and has formed in its inner or rear edge a series of transverse serrations or teeth d, which, when pressure is applied to the plowshare I, engage with the correspondingly-shaped teeth e in the inner face of the bar G', which forms the rear or inner end of the slot or opening through the arm G, as shown in Figs. 3 and 5. The bar J also has set in one side thereof, preferably between the ears F' and the arm G, a stud f to receive one end of a link connection f' between the bar J and the arm g, firmly secured upon the rocker-shaft K, mounted in bearings in the stands h h, bolted to the outer vertical face of the pilot-board E and projecting upward therefrom. The shaft K also has firmly secured thereon the upwardly-projecting arm i, to the upper end of which is connected one end of the rod j, the other end of which is connected to one end of the chain k, which, after passing partially around the sheave l, mounted in a stand secured to the under side of the sill of the platform, has its other end secured to the lower end of the lifting-rod m, the upper end of which is provided with a handle n, by lifting which the scraper or plowshare may be raised out of action whenever it is not desired in operation.

The link connection between the bar J and the arm g may consist of a plurality of chain-links f', as shown in Fig. 1, or of a single slotted link, as shown in Figs. 8 and 9, or any other form of connection may be used that will permit the bar J and plowshare I to be lifted by a movement of the rocker-shaft K about its axis in the direction indicated by the arrow in Fig. 1, and also permit said bar and plowshare to be lifted independently of any movement of said rocker-shaft when said plowshare comes in contact with a paving-stone or other obstruction.

L is a casing surrounding the upper portion of the lifting-rod m and provided with the vertical slot m' for the passage of the handle n, said slot being expanded at its upper end 5 to form the shoulder or catch m², upon which the handle n rests when the bar J and the plowshare I are raised to throw them out of operation.

If the scraper or plowshare I should come 10 in contact with a paving-stone that projects above the general level, the lower end of the bar J will be moved toward the rear till the teeth d engage the teeth e on the contiguous side of the bar G', when said bar and scraper 15 will be moved upward, so as to pass over the obstruction, moving the rear end of the arm G upward against the tension of the spring H, and as soon as the obstruction is passed the bar J and its scraper will drop again into 20 contact with the rail by the force of gravity assisted by the tension of the spring H.

The rear end of the arm G is normally located at a lower level than the axis of its pivot, and as a consequence when the teeth 25 d on the bar J engage the teeth e in the bar G' of the arm G and the scraper meets an obstruction in the shape of a paving-stone that is raised slightly above the general level the scraper is moved obliquely upward and 30 toward the rear till it will pass over the obstruction.

What we claim as new, and desire to secure by Letters Patent of the United States, is—

1. In a track-cleaner for street-cars the 35 combination with the truck-frame of the car, of a stand carried by said frame and provided with a guideway-slot in its upper portion; a radius-arm pivoted at one end to said stand and provided with a vertical slot through the 40 same; a scraper or plowshare to contact with the track-rail and provided with or secured to a shank or bar projecting upward through the slots in said radius-arm and stand and having its upper end portion curved toward 45 the end of the car; a series of teeth formed on the rear edge of said scraper-bar; a second

series of teeth formed in the rear end of the slot through said radius-arm adapted to engage said first series of teeth; and means carried by said truck-frame for raising said 50 scraper when not required for use.

2. In a track-cleaner for street-cars the combination with the truck-frame of the car and its pilot-board, of the stand F F'; the arm G pivoted to said stand, and provided 55 with the shoulders b and c and having a vertical slot through the same provided in its rear end with the teeth e; the scraper I; the scraper-carrying bar J having a curved upper portion and provided in its rear edge with 60 the teeth d; the spring H engaging the shoulder b of the arm G; the rocker-shaft K mounted in bearings in the stands h secured to said pilot-board; the arms g and i firmly secured on said shaft; a slotted link connection between said bar J and arm g; and means for partially rotating said shaft K to raise 65 said scraper.

3. In a track-cleaner for street-cars the combination with the truck-frame of the car 70 and its pilot-board of the stand F F'; the arm G provided with the shoulders b and c and having a vertical slot through the same provided in its rear end with the teeth e; the scraper I; the scraper-bar J provided with 75 the teeth d; the spring H; the stands h h; the rocker-shaft K; the arms g and i all carried by the pilot-board of the truck-frame; the rods j and m, the chain k; the sheave l; the handle n; and the casing L provided with 80 the slot m' and the shoulder or catch m² all constructed, arranged, and operating substantially as and for the purposes described.

In testimony whereof we have signed our names to this specification, in the presence of 85 two subscribing witnesses, on this 8th day of October, A. D. 1897.

GEORGE A. PARMENTER.
STEPHEN H. PEIRCE.
